THREE SIDED RADIO TUNING INDICATOR FACE PLATE

Maurice D. Katz, 35 Broadway, Lawrence, N.Y. 11559

Filed May 18, 1971, Ser. No. 144,702

Term of patent 14 years

Int. Cl. D14—03, 99

U.S. Cl. D26—1

FIG. 1.

FIG. 2.

FIG. 3.

FIG. 4.

FIG. 5.

FIG. 6.

FIG. 7.

FIG. 8.

FIG. 1 is a front perspective view of the three sided radio tuning indicator face plate, embodying the features of my new design,

FIG. 2 is a side elevational view,

FIG. 3 is an end elevational view, and

FIG. 4 is a front perspective view of a modified form of the three sided radio tuning indicator face plate, with one of the sides projecting at an angle from the common plane.

I claim:

The ornamental design for a three sided radio tuning indicator face plate, substantially as shown and described.
